(57) **ABSTRACT**

A new *Osteospermum* plant particularly distinguished by pink flowers with white rings and good branching, is disclosed.

1 Drawing Sheet

2

1. Single, pink flowers with white rings at the center of the flowers; and
2. Good branching.

5 **DESCRIPTION OF THE PHOTOGRAPH**

This new *Osteospermum* plant is illustrated by the accompanying photograph which shows a close-up the foliage, buds, and mature flower. The photograph is of a 12-week-old 10 plant grown outdoors in Stuttgart, Germany in June 2022. The colors shown are as true as can be reasonably obtained by conventional photographic procedures.

15 **DESCRIPTION OF THE NEW VARIETY**

The following detailed descriptions set forth the distinctive characteristics of 'KLEOE22715'. The data which define these characteristics were collected in Stuttgart Germany in May 2023 on plants potted in week 8. Color 20 references are to The R.H.S. Colour Chart of The Royal Horticultural Society of London (R.H.S.), 5th edition (2007). Classification:

Family.—Asteraceae.

Botanical.—*Osteospermum ecklonis* Norl.

Common.—*Osteospermum*.

Designation.—'KLEOE22715'.

25 Parentage:

Female parent.—The proprietary female *Osteospermum* variety 'OE-2017-4277' (unpatented).

SUMMARY

The following are the most outstanding and distinguishing characteristics of this new variety when grown under normal horticultural practices in Stuttgart, Germany.

<i>Male parent.</i> —The proprietary male <i>Osteospermum</i> variety 'OE-2016-3228' (unpatented).		Length.—0.5 cm.
Plant:		<i>Diameter (at apex).</i> —0.1 cm.
<i>Form and habit.</i> —Herbaceous perennial but usually cultivated as an annual; not frost resistant.	5	<i>Apex.</i> —Acute.
<i>Growth habit.</i> —Upright.		<i>Apex color.</i> —RHS 159A.
<i>Branching habit.</i> —Normal.		<i>Base.</i> —Acute.
<i>Height (from top of soil, including inflorescence).</i> —17.0 cm.	10	<i>Base color.</i> —RHS 157A.
<i>Width (including inflorescences).</i> —21.0 cm.		<i>Margin.</i> —Entire.
<i>Propagation.</i> —Vegetative terminal cuttings.		<i>Ray floret:</i>
<i>Time to produce a finished flowering plant.</i> —10 to 17 weeks.		<i>Quantity per inflorescence.</i> —22.
<i>Time to initiate and develop roots.</i> —4 weeks.	15	<i>Shape.</i> —Oblanceolate.
<i>Root description.</i> —Fine, white (RHS 155C).		<i>Color.</i> —Upper surface: RHS 70A with RHS NN155A ring (at the time of evaluation of the plant) and broad RHS N80B center with very weak longitudinal stripes. Lower surface: RHS 1D with RHS N137A light stripes.
Stems:		<i>Length.</i> —3.5 cm.
<i>Total number of branches per plant (calculated at the base of the plant).</i> —6.		<i>Width.</i> —0.9 cm.
<i>Length.</i> —11.0 cm.	20	<i>Apex.</i> —Obtuse.
<i>Diameter.</i> —0.3 cm.		<i>Base.</i> —Acute.
<i>Internode length.</i> —0.9 cm.		<i>Margin.</i> —Entire.
<i>Color.</i> —RHS 145A.		<i>Texture (upper and lower surfaces).</i> —Smooth.
<i>Texture.</i> —Smooth.		<i>Peduncle.</i> —Length: 3.4 cm. Diameter: 0.2 cm. Texture: Smooth with hairs. Color: RHS 144B.
<i>Anthocyanin.</i> —Absent.		25 <i>Phyllaries:</i>
Leaves:		<i>Texture.</i> —Smooth with fine hairs.
<i>Arrangement.</i> —Alternate.		<i>Color.</i> —RHS 143B.
<i>Shape.</i> —Obovate.		<i>Arrangement.</i> —Single.
<i>Apex.</i> —Acute.		<i>Observed quantity per plant.</i> —21.
<i>Base.</i> —Acute.	30	<i>Shape.</i> —Lanceolate.
<i>Margin.</i> —Serrate.		<i>Color.</i> —Upper surface: RHS 143B. Lower surface: RHS 145A.
<i>Margin indentation.</i> —Medium.		<i>Length.</i> —1.0 cm.
<i>Immature color.</i> —Upper surface: RHS 137B. Lower surface: RHS 138A.		<i>Width.</i> —0.2 cm.
<i>Mature color.</i> —Upper surface: RHS N137A. Lower surface: RHS 147B.	35	<i>Apex.</i> —Acute.
<i>Length.</i> —4.0 cm.		<i>Base.</i> —Obtuse.
<i>Width.</i> —2.2 cm.		<i>Margin.</i> —Entire.
<i>Texture and appearance.</i> —Upper surface: Leathery. Lower surface: Leathery with fine hairs.	40	<i>Texture.</i> —Upper surface: Smooth with fine hairs. Lower surface: Smooth.
<i>Petioles.</i> —Absent.		Reproductive organs:
<i>Venation pattern.</i> —Pinnate.		<i>Androecium location.</i> —On the disc floret.
<i>Venation color.</i> —Upper surface: RHS 144A. Lower surface: RHS 144A.		<i>Stamens.</i> —Quantity: Numerous, 50-100. Shape: Filamentous. Filament length: 0.4 cm. Filament diameter: Less than 0.1 cm. Anther: Shape: Lanceolate. Color: RHS N77A. Length: 0.1 cm. Diameter: Less than 0.1 cm. Pollen: Color: RHS 21A. Amount: Moderate.
Flower buds:	45	<i>Gynoecium location.</i> —On the base of the ray florets and disc florets.
<i>Shape.</i> —Round.		<i>Pistils.</i> —Number: Numerous, 50-100. Length: 0.3 cm. Diameter: Less than 0.1 cm.
<i>Length.</i> —0.9 cm.		<i>Stigma.</i> —Color: RHS N77A. Shape: Filamentous. Length: 0.2 cm. Diameter: Greater than 0.1 cm.
<i>Diameter.</i> —1.0 cm.		<i>Style.</i> —Color: RHS N77A. Length: 0.1 cm. Diameter: Less than 0.1 cm.
<i>Color (at tight bud just before the ray florets unfold).</i> —RHS 145A.	50	Fruit and seed set: None observed.
Inflorescence:		Disease and pest/insect resistance: No disease and pest/insect resistance observed.
<i>Type.</i> —Composite, single.		COMPARISON WITH PARENTAL LINES AND KNOWN VARIETY
<i>Blooming habit.</i> —Upright with longer flower stems.		
<i>Quantity of inflorescences per plant.</i> —6 at the time of evaluation of the plant; quantity depends on the stage of the plant and the environmental conditions.	55	
<i>Lastingness of the inflorescences on the plant.</i> —10 to 15 days.		
<i>Fragrance.</i> —Slightly present; fresh.		
<i>Inflorescence diameter.</i> —7.3 cm.		
<i>Inflorescence depth.</i> —0.5 cm.		
<i>Disc diameter.</i> —1.4 cm.		
Disc floret:		
<i>Quantity per inflorescence.</i> —About 100.		
<i>Shape.</i> —Tubular.	65	
<i>Tube color.</i> —Closed: RHS 155A. Mature: RHS 155A.		'KLEOE22715' is a distinct variety of <i>Osteospermum</i> and is distinguished from its parents as described in Table 1.

TABLE 1

Comparison with Parental Lines			
Characteristic	'KLEOE22715'	Female Parent	Male Parent
Flower filling	Single	Double	Single
Flower color	Pink with white ring	Pink with yellow filling	Pink-purple with pink center

'KLEOE22715' is most similar to the commercial *Osteospermum* variety 'KLEOE19396' (U.S. Plant Pat. No. 31,026). Differences between the varieties are described in Table 2.

TABLE 2

Comparison with Similar Variety		
Characteristic	'KLEOE22715'	'KLEOE19396'
Flower color	Pink with white ring	Orange with purple center
Branching	Good	Branching is not as good as 'KLEOE22715'

I claim:

1. A new and distinct cultivar of *Osteospermum* Plant Named 'KLEOE22715' as described and illustrated herein.
